UNITED STATES PATENT OFFICE.

GEORGE I. DE FORCE AND MOSES DRYFOOS, OF ERIE, PENNSYLVANIA.

SELF-LOCKING SPIKE.

1,084,405.

Specification of Letters Patent.

Patented Jan. 13, 1914.

Application filed December 27, 1912. Serial No. 738,835.

To all whom it may concern:

Be it known that we, GEORGE I. DE FORCE and MOSES DRYFOOS, citizens of the United States, and residents of Erie, in the county 5 of Erie and State of Pennsylvania, have made certain new and useful Improvements in Self-Locking Spikes, of which the following is a specification.

Our invention relates to spikes and more 10 particularly to devices of this kind known as self locking spikes, and used more especially upon railway tracks for holding the rails upon the cross ties.

More particularly stated our invention 15 comprehends a spike having all the advantages of an ordinary spike, and at the same time provided with shoulders of peculiar form for preventing the ready withdrawal of the spike from the wooden cross tie or 20 other analogous member into which the spike is driven.

Our invention further comprehends a spike having a special form of point for facilitating the entrance of the spike into 25 the wooden member with which it is associated.

Reference is made to the accompanying drawings forming part of this specification and in which like letters indicate like parts.

30 Figure 1 is a perspective view of our improved spike, and Fig. 2 is a cross section on the line 2—2 of Fig. 1.

A shank 3 is provided with a head 4 integral with it and also with a point 5, the latter having the proximate form of a wedge. The point 5 is provided upon its opposite faces with fins 6, which extend for a little distance along the sloping or tapering part of the shank, as will be understood from 35 Fig. 1. The fins 6 serve as cutting edges and facilitate the entrance of the point 5 into the cross tie. The shank 3 is provided with a groove 7 and with a shoulder 8, the groove having a substantially triangular 40 cross section, as will be understood from Fig. 2, and the shoulder 8 being also of a general triangular form. There are two of the grooves 7, shown located upon each side of the shank 3.

50 The operation of our device is as follows:

The spike being made as above described the point 6 is placed upon the cross tie or other wooden member into which the spike is to be driven, the head 4 being brought adjacent to the foot of the rail in a manner well understood in this art. The spike is now driven into the cross tie. The fins 6 by serving as cutting edges facilitate the entrance of the spike into the cross tie. After the spike is driven well down into the cross tie the 60 shoulder prevents the ready withdrawal of the spike. This is because the wood of which the cross tie is composed, being more or less springy and disposed to regain its original form, projects into the groove 7 and 65 lodges directly against the shoulder 8 so as to slightly overhang the latter. If now an effort is made to withdraw the spike the shoulder 8 tightens against the overhanging particles of wood of the cross tie and 70 prevents the extraction of the spike.

We do not limit ourselves to the exact form shown, as variations may be made in our invention without departing from the spirit thereof as set forth in the claims annexed.

Having thus described our invention what we claim as new and desire to secure by Letters Patent is as follows:

1. A spike comprising a shank provided 80 with a head and with a point, and also provided upon one of its faces with a groove bounded by a shoulder to prevent the easy withdrawal of the spike, said point being provided with inclined flat faces and with 85 projecting fin portions of greater width than the point and extending perpendicularly from said inclined faces.

2. A spike comprising a shank and a head integral therewith, said shank being provided with a groove and with a shoulder bounding said groove to prevent the easy withdrawal of said spike, said shank being provided with a cutting portion having faces inclined relatively to each other, said 95 cutting portion being further provided with fins integral with said portion and extending therefrom in planes perpendicular to said inclined faces.

3. A spike comprising a shank provided 100

with a head and with a point, said shank being provided upon its oppositely disposed faces with two grooves, each groove reaching nearly the entire distance from the head 5 to the point, and being bounded at one end of said groove by a shoulder, said point being provided with inclined flat faces each

terminating adjacent to the oppositely disposed shoulders.

GEORGE I. DE FORCE.
MOSES DRYFOOS.
